UNITED STATES PATENT OFFICE.

HUGO GERNSBACK, OF NEW YORK, N. Y.

COIL MOUNTING.

Application filed February 24, 1923. Serial No. 621,048.

To all whom it may concern:

Be it known that HUGO GERNSBACK, a citizen of the United States, residing at New York, in the county of New York and 5 State of New York, have invented certain new and useful Improvements in a Coil Mounting, of which the following is a specification.

This invention relates to coils for radio 10 work and the primary objects of the invention are, first to provide novel means for mounting the coils proper in place, and second novel means for associating the coils proper with the base, whereby the coils can 15 be readily put in or pulled out of the circuits.

Another prime object of the invention is to provide a coil embodying a base provided with a plurality of novelly arranged 20 sockets, so disposed as to permit the swinging thereof, and novel elongated handles or blades upon which the coils proper, preferably of the spider web type are mounted, the sockets permitting the adjusting of the 25 coils in relation to one another.

A further object of the invention is to provide novel means for mounting the spider web coils proper upon the handles or blades, each blade or handle having a 30 plug formed of insulating material detachably connected therewith for receiving the spider web coils, the reinforcing element of the spider web coils engaging the plug, whereby displacement thereof is precluded, 35 the blades or handles carrying novel contacts for engaging the sockets.

With these and other objects in view, the invention consists in the novel construction, arrangement and formation of parts, as will 40 be hereinafter more specifically described, claimed and illustrated in the accompanying drawings, in which drawings:

Figure 1 is an elevation of the improved coil, showing one of the coils proper connected with the base.

Figure 2 is a top plan view of the base for supporting the different coils.

Figure 3 is a section through the improved coil taken on the line 3-3 of Figure 1.

Figure 4 is a fragmentary perspective view of the base showing the novel means for mounting one of the sockets on the base.

Figure 5 is a detailed perspective view showing the lower contact end of one of the handles or blades which carry the coils proper.

Figure 6 is a detail longitudinal section through a portion of the device taken on the line 6-6 of Figure 7 showing the means of mounting one of the blades or handles in 60 one of the sockets.

Figure 7 is a transverse section through a portion of the improved device taken on the line 7-7 of Figure 6 illustrating the means for mounting one of the blades or 65 handles in one of the sockets.

Figure 8 is a detail horizontal section taken on the line 8-8 of Figure 6 illustrating the means of connecting one of the blades or handles to one of the sockets and 70 the means for connecting the terminals of one of the coils proper with the contacts carried by the said blade or handle.

Referring to the drawings in detail, 75 wherein similar reference characters designate corresponding parts throughout the several views, the letter A generally indicates the improved device, which includes the base B, which is of novel construction, the handles or blades C and the novel coils proper D carried by the said handles or blades C.

The base B is constructed from insulating material and includes a base plate 10 having depending base flanges 11 formed on the marginal edges thereof, which form a 85 support for the said base plate 10 and permit the spacing thereof from the support upon which it may be placed.

Disposed upon the upper surface of the base plate 10 at equi-distant spaced points 90 are pairs of supporting brackets 12, 13 and 14. These pairs of brackets 12, 13 and 14 are constructed of electric conducting material and the brackets of each pair are disposed in longitudinal alignment, while the 95 pairs of brackets are disposed in transverse alignment, and each bracket is of substantial L-shape when viewed in elevation and includes the attaching portion 15 and the 100 upstanding arm 16.

As shown the attaching portion 15 of the central pair of supporting brackets 13 are relatively longer than the attaching portion of the end pairs of supporting brackets 12 and 14. These brackets are held in place 105 by suitable retaining binding posts or the like 17, which form binding posts for the various electric conducting wires as can be readily understood by those skilled in the art. The binding posts of the central pair 110 of supporting brackets 15 are disposed beyond the retaining screws and binding posts.

17 of the end pairs of retaining brackets 12 and 14.

The arms 16 of the retaining brackets support the sockets 18 for a purpose, which will 5 be hereinafter more fully described.

The sockets 18 carried by the various pairs of brackets 12, 13 and 14 are of the same construction but it is preferred to have the sockets carried by the end portions of the 10 brackets mounted for rocking movement, while the socket carried by the central pair of brackets 13 is preferably rigidly secured to the said central pair of brackets.

Each of these sockets however, include a 15 spacing block of insulation 20 and upstanding resilient contact arms 21. These arms 21 are substantially U-shaped in cross section and form guides for the removable portions or handles C of the device.

20 As shown the lower portions of the sockets are offset slightly and connected with the end portions of the spacing block of insulation 20 and these connecting portions of the sockets are adapted to be in intimate contact with the arms 16 of the various brackets at all times. Suitable retaining screws or the like 22 extend through the arms 16 of the various brackets through the sockets 21 and into the spacing blocks 20. By this 25 construction it is obvious that said sockets can freely swing on the brackets. The screws which support the central socket are preferably screwed into the spacing blocks relatively tight, so as to prevent the swinging of the said block and socket carried thereby.

30 The handles or blades C each include an elongated thin flexible body 25 formed of insulating material and if so desired the 40 said bodies can gradually taper toward their free ends.

In the drawings I have only illustrated 45 one handle and one coil connected with the base but it is to be understood of course that each of the sockets 18 can have one of the handles connected therewith.

50 Disposed intermediate the ends of the handle C is arranged a plug 30 of insulating material having an annular flange 31 formed at one end thereof. This plug is adapted to be secured to the handle by a suitable movable screw or the like 32 and extends through the handle and through the axial center of the said plug.

55 The coil D carried by the handle is preferably of the spider web type or flat inductance type constructed in accordance with my pending application filed Feb. 9, 1923, Serial Number 618,075. The plug 30 60 extends through the axial center of the coil D and the reinforcing pins 33 of the coil are adapted to engage said plug and thus the plug tends to hold the reinforcing pins in place. The annular flange 31 engages 65 the outer face of the coil and the inner face

of the coil is adapted to engage the handle C, whereby when the plug is placed in position accidental displacement of the coil is precluded. The terminals 34 and 35 of the coil are connected to contacts 36 and 37 70 which are of like construction. As shown each of the contacts include a metal plate bent around the opposite edges of the handle C at the lower end thereof and these plates are held on the handle by means of 75 suitable rivets or the like 38, which also form means for holding the terminals 34 and 35 in engagement with said plates. These contact plates 36 and 37 are adapted to engage the guide portions 21 of the sockets 18 and it is evident that these handles can be readily removed from the said sockets when so desired.

80 It is also to be noted that when a handle is placed in a socket, that the same will 85 tend to spread or spring the socket outward, and thus tend to move the same in further contact with the arms 16 of the pairs of brackets 12, 13 and 14.

85 Owing to the means of mounting the end 90 sockets 18 in position, the coils carried by the end handles can be swung toward or away from the central handle and coil to permit the various adjustments to be had, 95 as may be necessary.

95 From the foregoing description it can be seen that a novel radio coil unit has been provided of exceptionally simple and durable construction in which the coils proper can be readily and quickly associated with 100 or removed from the base.

Changes in details may be made without departing from the spirit or the scope of this invention.

105 What I claim as new is:—

1. A coil unit for radio work comprising a base, pairs of angle brackets formed of electric conducting material secured to the base, binding posts connected with the brackets, electric conducting sockets secured to and between the pairs of brackets, said sockets forming terminal members respectively for engaging the brackets, a removable manipulating handle detachably connected with each pair of sockets, a removable coil associated with each handle, and terminal members for the coil associated with the handle for engaging the sockets. 115

120 2. A radio coil unit comprising a base constructed of insulating material, a plurality of pairs of angle brackets connected with the base, socket members connected with the angle brackets, each of said socket members including a spacing block of insulation and end members of conducting material U-shaped in cross section for engaging the angle brackets and connected with said spacing block, handles of insulating material, contacts carried by the lower ends of said 125 handles, the handles being adapted to be de- 130

- tachably fitted within said U-shaped guides of the sockets, and coils connected with said handles having their terminals thereof secured to said contacts.
- 5 3. A radio coil unit comprising a base formed of insulating material, pairs of angle brackets formed of electric conducting material connected with said base, each of said brackets including an attaching leg and
- 10 an upstanding arm, sockets connected with pairs of brackets each including a spacing block of insulating material and end members connected with the block at the terminals thereof formed of electric conducting
- 15 material and including upstanding guide portions U-shaped in cross section, means extending through the upstanding arms of the angle brackets and into said end members and the spacing blocks, handles formed of
- 20 insulating material adapted to fit in said guide portions of said end members, contact plates secured to the lower end of said handles and extending around the opposite edges thereof for engaging said guide portions, and coils secured to said handles and
- 25 connected with said contact plates.
4. In a radio coil unit, a handle formed of insulating material, a coil carried by said handle, contact plates secured to the lower end of said handle at the opposite sides thereof and connected with the terminals of the coil, and curved portions formed on said plates extending around the opposite edges of said handle. 80
5. In a radio coil unit for the purpose specified, a handle formed of insulating material, a flat inductance coil including a body and a plurality of reinforcing pins extending through the body formed of insulating material and terminating at the inner periphery of the coil, a plug of insulating material fitted in said coil engaging the inner ends of said pins, an annular flange formed on the outer face of the plug engaging the outer face of the coil, the inner face of the plug being fitted against said handle, and a retaining member extending through said handle and through the axial center of said plug for retaining the plug in firm contact with the handle. 85 40 45 50

In testimony whereof I affix my signature.
HUGO GERNNSBACK.
